UNITED STATES PATENT OFFICE.

HENRY C. ZENKE, OF RICHMOND HILL, NEW YORK.

FIG.

Application filed October 11, 1922. Serial No. 593,737.

To all whom it may concern:

Be it known that I, HENRY C. ZENKE, a citizen of the United States, residing in Richmond Hill, county of Queens, State 5 of New York, have invented an Improvement in Pigs, of which the following is a specification.

My present invention relates to the supply of metal to line casting machines, and 10 particularly to a pig of a new form which is designed to be used in automatic feeding devices.

Several of these are on the market and their operation depends to a great extent 15 upon the height of metal in the melting pot of the machine to which it is supplied, a float in which controls the action of the automatic feeders. The most satisfactory feeders use pigs of considerable size and 20 weight, twenty-five pounds or more, and the common form of such devices is satisfactory for ordinary operation; but I have found that with unusually rapid operators, or, in some cases, with class of matter which re- 25 quires a large amount of metal, as where the type faces are very large, the ordinary pig does not melt rapidly enough and the metal in the melting pot becomes chilled and does not work well. It is the object 30 of the present invention to obviate this difficulty, which I do by a change in the shape of the pig, presently to be described.

The accompanying drawings show one of the pigs of my invention,

35 Figure 1 being a perspective of the pig which I have devised;

Figure 2 an alternative construction; and

Figure 3 being an end elevation of a pig of the ordinary character.

40 Pigs of the ordinary character, as illustrated by Figure 3, have so large a body of metal contained in them that they do not melt fast enough when dipped in the hot metal of the pot. I therefore arrange to 45 give them an extended heat absorbing surface by molding, or otherwise forming them, with ribs between which grooves extend, preferably longitudinally of the pig, though not necessarily so. Such a form of pig is

shown in Figure 1 in which A is the pig, 50 A¹ is the longitudinal groove formed on the narrower surface thereof; A² is a cut-away portion which facilitates the insertion of the pig into the feeding device. A⁴, A⁴ are ribs between which the groove A¹ is 55 located. In this form of the improved pig, there is only one groove.

Figure 2 shows another form of pig which in general is like the pig in Figure 1, but is provided with additional grooves A³, A³. 60 This pig is adapted to the most rapid work on large type demanding extraordinary supply of metal and the surface is even more extended than that shown in Figure 1, so that it melts with considerably increased 65 rapidity.

It is obvious that it is not important by what method the pig may be formed. That formed in Figure 2, for example, might be cast in a flat sheet and then run between 70 corrugating rollers; but whether cast or otherwise formed, it would be within my invention.

In the claims, I have used the phrase "a number of grooves" and I mean thereby 75 one or more, as may be considered desirable, the object being to provide a pig of type metal with an extended heat absorbing surface formed by the grooves and ribs so that it will melt with sufficient rapidity to supply the machine under all circumstances. 80

I claim:

1. A pig of metal for use in a line-casting machine, having an extended heat-absorbing surface formed by a number of 85 grooves in the metal.

2. A pig of type-metal having a number of longitudinal grooves forming an extended heat-absorbing surface.

3. A pig of type-metal having ribs on 90 which the pig may slide in a feeder, and one or more intermediate grooves between the ribs, forming an extended heat-absorbing surface.

In testimony whereof, I have signed my 95 name to this specification this 9th day of October, 1922.

HENRY C. ZENKE.
